[57] CLAIM

The ornamental design for handle for a drawer or similar article, substantially as shown and described.

DESCRIPTION

FIG. 1 is a front perspective view of handle for a drawer showing my new design;

FIG. 2 is a top view;

FIG. 3 is a bottom view;

FIG. 4 is an end view;

FIG. 5 is a rear view;

It is noted that the other end view is substantially identical to the end view of FIG. 4.
